UNITED STATES PATENT OFFICE.

WILLIAM H. HAMILTON, OF MCKEESPORT, PENNSYLVANIA.

SHIRT-WAIST.

SPECIFICATION forming part of Letters Patent No. 728,571, dated May 19, 1903.

Application filed August 7, 1901. Serial No. 71,227. (No model.)

To all whom it may concern:

Be it known that I, WILLIAM H. HAMILTON, a citizen of the United States of America, residing at McKeesport, in the county of Allegheny and State of Pennsylvania, have invented certain new and useful Improvements in Shirt-Waists, of which the following is a specification, reference being had therein to the accompanying drawings.

This invention relates to certain new and useful improvements in shirt-waists, and has for its object the provision of novel means whereby a shirt-waist may be easily attached to the trousers; furthermore, one wherein the suspenders may be worn within the shirt-waist and provide means for fastening and retaining the suspenders in position.

The invention has for a further object to construct a shirt-waist of the above-described class that will be extremely simple in construction, strong, durable, and comparatively inexpensive to manufacture.

With the above and other objects in view the invention consists in a shirt-waist having a waistband connected to the inner face of the shirt-waist, straps attached to said waistband extending into the shirt-waist and through the same, the inner ends of said straps carrying buttons or other suitable fastening means and the outer extensions of said straps being provided with buttonholes.

The invention further consists in the novel combination and arrangement of parts to be hereinafter more fully described, and specifically pointed out in the claims.

In describing the invention in detail reference is had to the accompanying drawings, forming a part of this specification, and wherein like numerals of reference indicate corresponding parts throughout the several views, in which—

Figure 1 is a plan view of one side of the inner portion of a shirt-waist. Fig. 2 is a vertical sectional view of the lower portion thereof.

In the drawings the reference-numeral 1 indicates the shirt-waist, 2 the sleeves thereof, 3 the neckband, and 4 the waistband se-

cured to the inner face of the shirt-waist, said waistband having attached thereto straps 5, extending in the inner side of said shirt-waist, these straps extending through said shirt-waist to the front thereof, as shown at 6, the inner ends of the straps carrying buttons 7 or other suitable fastening means for the suspenders, while the outer extensions of the straps are provided with buttonholes 8. The reference-numeral 9 indicates a strap arranged upon the shoulder portion to retain the suspenders in position.

The manner of wearing my shirt-waist is as follows: The suspenders being applied to the buttons 7, a series of straps being arranged around the entire garment, two at each side of the same and two in the rear of the same, the suspenders being in position, the shirt-waist is then secured in the ordinary manner, the lower ends of the straps 6 fastened to the buttons secured upon the trousers.

The many advantages obtained by the use of this shirt-waist will be readily apparent from the foregoing description, taken in connection with the accompanying drawings, and it will be noted that various changes may be made in the details of construction without departing from the general spirit of my invention.

Having fully described my invention, what I claim as new, and desire to secure by Letters Patent, is—

1. In a shirt-waist, an interior waistband, straps rigidly secured to said waistband between the same and the waist, said straps each having an upwardly-extending portion carrying a button on the interior of the waist, and a portion extending on the exterior downwardly through apertures provided therefor in the said waist and having a buttonhole formed therein, substantially as described.

2. In a shirt-waist, a waistband secured to the interior thereof, straps secured to said waistband with a portion carrying buttons extending on the interior of the waist, and a portion extending through apertures pro-

vided therefor on the exterior of said waist, the said second-named portion having buttonholes formed therein adapted to be engaged by the buttons carried by the trousers, 5 and the said portion carrying the buttons adapted to engage the suspenders, substantially as described.

In testimony whereof I affix my signature in the presence of two witnesses.

WILLIAM H. HAMILTON.
